United States Patent Office

Des. 181,350
Patented Nov. 5, 1957

181,350

HOUSE

William C. Fitt, Birmingham, Mich.

Application August 15, 1956, Serial No. 42,610

Term of patent 7 years

(Cl. D13—1)

FIG. 1

FIG. 2

FIG. 3

Fig. 1 is a perspective view of a house embodying my design.

Fig. 2 is a front elevational view thereof.

Fig. 3 is a rear elevational view thereof.

The essential features of my design reside in the portions shown in full lines.

I claim:

The ornamental design for a house, as shown and described.
